[57] CLAIM

The ornamental design for an embroidery machine, as
shown and described.

DESCRIPTION

FIG. 1 is a top plan view of an embroidery machine
showing my new design;

FIG. 2 is a bottom plan view thereof;

FIG. 3 is a front elevational view thereof;

FIG. 4 is a rear elevational view thereof;

FIG. 5 is a left side elevational view thereof;

FIG. 6 is a right side elevational view thereof;
FIG. 7 is a top front perspective view thereof, with the
movable frame of the embroidery machine shown in an
alternate position;

FIG. 8 is a bottom rear perspective view thereof, with
the legs of the stationary base plate shown in their re-
tracted position; and

FIG. 9 is a top front perspective view thereof with a
sewing machine shown in broken lines for illustrative
purposes only.

FIG. 1

FIG. 3

FIG. 4

FIG. 2

FIG. 5

FIG. 6
